UNITED STATES PATENT OFFICE.

ALLEN MIDDLETON, JR., OF PHILADELPHIA, PENNSYLVANIA.

IMPROVEMENT IN CAR-COUPINGS.

Specification forming part of Letters Patent No. 142,492, dated September 2, 1873; application filed January 2, 1873.

To all whom it may concern:

Be it known that I, ALLEN MIDDLETON, Jr., of Philadelphia, Pennsylvania, have invented a Spring-Coupling for Railroad-Cars, of which the following is a specification:

The object of my invention is to obviate the severe strains to which railroad-cars are subjected on starting trains, and this object I attain by means of a rod, A, or its equivalent, connected to bumper and draw-heads B at both ends of the car, and operating in conjunction with springs D D', substantially as shown in the inverted plan view in the accompanying drawing, so that in starting the train the pulling-force exerted at one end of the car will be exerted, through the medium of the spring, at the opposite end of the car, and will be transmitted through the entire frame-work, the said springs also serving as bumper-springs to absorb the shocks which take place when the cars meet.

G represents the frame-work of an ordinary car, and near the opposite ends of the same are secured springs D and D', each consisting in the present instance of two side plates, a a, two cross-plates, b and b', and intervening elastic medium of any appropriate character. The rod A extends from one spring to the other, and passes through both springs, and has at each extreme end a head, d, contained within the adjoining draw and bumper head B so as to bear against shoulders in the same when the rod is drawn in one direction, but so as to slide freely in, and independently of, the bumper-head when the rod is drawn in the opposite direction.

Supposing the bumper-head B at the end of the car to the right to be drawn in the direction of the arrow, the rod A must necessarily follow, and this it will do without acting upon the spring D'; it will, however, pull the draw-head at the opposite end of the car against the plate b of the spring D, the elastic medium of which will, in a measure, lessen the

shock, but the further pulling-force exerted by the rod to draw the car forward in the direction of the arrow will be transmitted through the entire frame-work of the car from the spring D outward; hence the frame cannot be subjected to the severe strains which, with the usual connections, it will experience on starting a train. When the car is drawn in a direction opposite to that pointed out by the arrow the pull takes place from the spring D', and when two cars meet the bumper-heads are forced against the plates b of the springs, and the latter consequently diminish the shocks.

It is not essential, in carrying out my invention, that the springs at the opposite ends of the car should be connected by a rigid bar, A, as a chain, or a system of links, or other equivalent connecting medium might be substituted for the said bar.

I am aware that the couplings at opposite ends of a car have been connected by longitudinal rods, and that springs have been arranged between each of said couplings and the end beam of the car. I, therefore, do not claim, broadly, couplings, rods, and springs so arranged; but

I claim as my invention—

The combination of the draft-rod J, extending from end to end of the car, with spring-boxes D and D', and draw-bars B and B', the draft-rod extending through both boxes and through their fixed and movable plates b' and b, and having at its opposite ends heads d adapted to the draw-bars, all substantially as and for the purpose specified.

In testimony whereof I have signed my name to this specification in the presence of two subscribing witnesses.

ALLEN MIDDLETON, JR.
